UNITED STATES PATENT OFFICE.

JEPHTHA M. NEWTON, OF DOTHAN, ALABAMA.

TENSIONING AND PULLING DEVICE.

1,400,371.

Specification of Letters Patent.

Patented Dec. 13, 1921.

Application filed January 26, 1921. Serial No. 440,244.

To all whom it may concern:

Be it known that I, JEPHTHA M. NEWTON, a citizen of the United States, residing at Dothan, in the county of Houston and State 5 of Alabama, have invented certain new and useful Improvements in Tensioning and Pulling Devices; and I do hereby declare the following to be a full, clear, and exact 10 description of the invention, such as will enable others skilled in the art to which it app pertains to make and use the same.

This invention relates to an improved device used for pulling stalled automobiles or other vehicles out of a mud hole, for 15 stretching fence wires or fences of the woven wire type, or for any other similar use.

One object of the invention is to provide a puller or stretcher of the type specified which is so constructed that the pulling or stretching 20 may be done with a minimum amount of labor and without danger of the grapple slipping and releasing the fence wires or article being pulled.

Another object of the invention is to so 25 construct this device that the amount of pull or stretch accomplished at one setting up of the device may be controlled.

Another object of the invention is to so 30 construct this device that it will be very simple in operation and very easy to set up.

Another object of the invention is to so 35 construct this device that it may be easily and cheaply produced and to further so construct it that it may be strong and durable and not liable to break.

This invention is illustrated in the accompanying drawings wherein:

Figure 1 is a side elevation of the improved device.

40 Figs. 2 is a longitudinal section taken along the line 2—2 of Fig. 1.

Fig. 3 is an enlarged view showing one of the ladder sections in side elevation.

Fig. 4 is a transverse sectional view taken 45 along the line 4—4 of Fig. 3.

Fig. 5 is a view showing one of the links in side elevation.

Fig. 6 is an enlarged view of one of the hooks engaging the ladder and carried by 50 the actuating lever.

Fig. 7 is a detail view of a portion of the lever.

Fig. 8 is a plan view of the link.

This device is provided with an actuating 55 lever 10 which will be engaged by a pivot bar or hook 11 extending from and con

nected with an anchoring post 12. The pivot rod or bar is detachably secured to the lever 10 thus permitting the lever to be released from this bar when it is desired to detach 60 the device until again used. Openings 13 are formed in this lever above and below the openings through which the hooked end of the pivot bar passes thus permitting the hooks 14 to be pivotally connected with the 65 lever and said hooks are headed to prevent them from being detached from said lever. These hooks will each be provided with a head 15 having an inclined cam edge 16 and a straight cut rear edge 17 so that the hooks 70 may have the proper action as will be hereinafter brought out. A ladder element is provided for engagement by the hooks 14 and will be formed of a plurality of sections 18 each of which will be provided with 75 upper and lower rows of openings 19 and 20, the openings of the upper row 19 being positioned in staggered relation to the openings of the lower row 20. Grooves 21 are formed in the sections 18 longitudinally 80 thereof and extend from one opening to another in each line of openings. It should be noted that grooves are so cut that they will start from the lower portion of one of the openings and terminate at the upper portion of the adjoining or following opening 85 or in other words that these grooves decrease in depth from one opening to another. Since the grooves decrease in depth from one opening to the other the straight cut edge 90 17 of the head 15 may obtain a firm grip upon the ladder sections when the head is resting in one of openings but may move easily out of the openings to a second opening through engagement of the inclined or 95 cam edge 16 with the sloping grooves. By having the openings positioned in staggered relation the lever may be swung upon its pivot and one of the hooks 14 moved to exert a strain upon the ladder structure or element while the second hook is moving 100 through the groove from one opening to another. These sections 18 which constitute the ladder are connected by links 22 which are formed of heavy rod metal and having 105 arms passing through openings 23 formed in the ladder sections. It will thus be seen that any number of ladder sections may be provided according to the amount of pull it is thought it will be necessary. This ladder 110 element has a chain element connected with it, the chain element being formed of a plu-

rality of links 24 each of which is provided with large ends 25 having openings 26 formed therein thus permitting the links to be connected by U-shaped fasteners 27. One 5 of these fasteners 27 will be used for connecting the inner links of the chain elements with the ladder element. As many links may be used as will be found desirable according to the length of the chain 10 required. This chain element will have a suitable engaging element connected with its outer link so that the chain element may be connected with the axle of an automobile, with the fence wires or woven fabric forming the fence or with any other object with 15 which it is desired to pull or stretch.

When in use the anchor post 12 will be driven into firm ground and the actuating lever will be connected with this anchor post 20 through the medium of the pivot bar. It is obvious that if desired or convenient a tree could be made use of and a chain or flexible cable passed about the tree and connected with the pivot bar. The chain element will 25 be connected with the automobile or other object upon which it is desired to exert a pulling force and the hooks 14 will then be positioned to engage the openings of one of the links or sections forming the ladder. 30 The lever may now be rocked upon the pivot bar and in doing so the hooks will move from one opening to another through the grooves of the ladder sections. It will thus be seen that the ladder element and chain 35 element may be drawn tight and held tight by one hook while the second is moving from one opening to another to obtain a new grip upon the ladder element. It is therefore only necessary to oscillate the lever in order 40 to exert a pulling force to withdraw an automobile from a mud hole, stretch a fence wire, or woven wire fencing or to exert a pulling action upon an object if it is desired to pull or stretch. After the automobile or 45 other object has been moved as far as permitted by the hooks reaching the end of the ladder section the anchor post may be removed and again driven into the ground at a point removed from the automobile and the 50 operation repeated. After the automobile has been extracted from the mud or the fence stretched as tight as desired the device may be taken apart and packed away in a small space. There has therefore been provided 55 a device of the character described which is very efficient in operation and very easy to operate.

What is claimed is:—

1. A device of the character described comprising an anchoring element, an actuating

lever pivotally connected with the anchoring element, a ladder element having longitudinally extending rows of openings with the openings of one row positioned in stepped relation to the openings of the second row, hooks 65 pivotally connected with the actuating lever upon opposite sides of the pivot point thereof and having heads for fitting into the openings of the ladder elements, the ladder elements provided with longitudinally extending 70 grooves connecting the openings and decreasing the depth from one opening to another, the free ends of the hooks being cut at an incline to provide cam edges causing the hooks to ride easily from one opening to another, and a 75 chain element connected with the ladder element.

2. A device of the character described including a pivotally mounted actuating lever, 80 hooks loosely connected with the actuating lever upon opposite sides of the pivot point thereof, and article engaging means including a ladder structure provided with longitudinally extending rows of openings positioned in staggered relation, the ladder structure 85 being provided with grooves leading from one opening to another and decreasing in depth from one opening to another.

3. A device of the character described including a pivotally mounted actuating lever, 90 hooks connected with the actuating lever upon opposite sides of the pivot point thereof, and article engaging means including a ladder structure formed of a plurality of loosely connected links each provided with 95 longitudinally extending rows of openings positioned in staggered relation and each shank being provided with grooves connecting the openings of the rows and decreasing in depth from one opening to another. 100

4. A device of the character described including an article engaging means having a chain structure formed of a plurality of links having openings formed in the end portions thereof, fasteners passing through the openings of the links to loosely connect the same, a ladder structure having a plurality of links loosely connected, and an operating element including a lever, and hooks carried by the lever for engaging the ladder 105 structure and drawing the ladder structure and chain structure toward the operating element when the device is in operation. 110

In testimony whereof I affix my signature in presence of two witnesses.
